US00D897219S

(12) United States Design Patent (10) Patent No.: US D897,219 S
(45) Date of Patent:  *Sep. 29, 2020

(54) DISPENSING BOTTLE AND CAP IN COMBINATION

- (71) Applicant: Chubby Gorilla, Inc., Santa Fe Springs, CA (US)
(72) Inventor: Eyad Aboabdo, Fullerton, CA (US)
(73) Assignee: Chubby Gorilla, Inc., Fullerton, CA (US)
(*) Notice: This patent is subject to a terminal disclaimer.
() Term: 15 Years
(21) Appl. No.: 29/689,588
(22) Filed: Apr. 30, 2019

Related U.S. Application Data

- (63) Continuation of application No. 29/655,619, filed on Jul. 5, 2018, now Pat. No. Des. 860,004, and a continuation of application No. 29/655,623, filed on Jul. 5, 2018, now Pat. No. Des. 855,476, which is a continuation of application No. 29/573,527, filed on Aug. 6, 2016, now Pat. No. Des. 834,950, and a continuation of application No. 29/573,527, filed on Aug. 6, 2016, now Pat. No. Des. 834,950.
